UNITED STATES PATENT OFFICE.

WILLIS J. PERKINS, OF GRAND RAPIDS, MICHIGAN.

SAFETY STARTING DEVICE.

1,145,436.

Specification of Letters Patent.

Patented July 6, 1915.

Application filed June 6, 1913. Serial No. 772,064.

To all whom it may concern:

Be it known that I, WILLIS J. PERKINS, a citizen of the United States, residing at Grand Rapids, Michigan, have invented certain new and useful Improvements in Safety Starting Devices, of which the following is a specification.

This invention relates to improvements in starting means for internal combustion engines, and the invention is especially adapted to use with engines for automobiles, although it may be made use of in engines for aeroplanes, motor boats and for any other purpose to which this class of engine may 15 be adapted.

The objects of the invention are to provide safety devices for starting such engines, the objects in detail being: first, to provide special means to avoid the back kick in 20 starting the engine. Second, to provide improved means of preventing the accidental starting of the vehicle, such as an automobile, when starting the engine. Third, to provide improved means of automatically cutting out and preserving the battery after 25 the engine has started. Fourth, to provide improved details of construction of the magneto devices. Fifth, to provide improved handle keeper socket and switch means associated therewith.

Objects relating to details of construction and arrangement of parts and the disposition and arrangement of switches for the purpose, and details and economies of construction and operation will definitely appear from the detailed description to follow.

I accomplish the objects of my invention by the devices and means described in the following specification.

40 The invention is clearly defined and pointed out in the claims.

Structures constituting preferred embodiments of my invention are illustrated partially in diagram in the accompanying 45 drawings, forming a part of this specification, in which:

Figure I is a diagrammatic view showing the connections and disposition and arrangement of parts of my invention when embodied and incorporated in an automobile with a Splitdorf magneto and ignition system. Fig. II is a longitudinal detail sectional view of my improved handle keeper

socket, and switch means, taken on a line corresponding to line 2—2 of Figs. III, IV 55 and V. Fig. III is a transverse enlarged detail sectional view taken on a line corresponding to line 3—3 of Fig. II, showing what I choose to call the anti-start switch and connections. Fig. IV is an enlarged detail sectional view taken on a line corresponding to line 4—4 of Fig. II, showing what I denominate the anti-kick switch and connections. Fig. V is an enlarged detail transverse sectional view taken on a line corresponding to line 5—5 of Fig. II, showing what I call the anti-battery switch and connections. Fig. VI is a diagrammatic view showing the wiring and connections of my engine as made use of in conjunction with 70 a Mea magneto. Fig. VII is a detail plan view of the Mea magneto, as illustrated in Fig. VI. Fig. VIII is an enlarged detail longitudinal sectional view through the handle socket taken on a line corresponding 75 to line 8—8 of Fig. IX. Fig. IX is an enlarged detail transverse sectional view taken on a line corresponding to line 9—9 of Fig. VIII.

In the drawing, all of the sectional views 80 are taken looking in the direction of the little arrows at the ends of the section lines, and similar parts are referred to by similar numerals throughout the several views.

Considering the numbered parts of the 85 drawing, the engine 1, of the four cylinder type each with a spark plug, is provided with a crank shaft 2 on which is a suitable crank 3 for starting the same. Equivalent starting means may be provided. A handle 90 keeper socket 4 is provided for the handle of the crank 3, in which are disposed switches that are automatically operated by applying or removing the handle keeper socket from the crank handle. The keeper 95 handle socket is secured by strap 5 to a convenient part of the machine. The socket is provided with a longitudinally disposed spring 6 against which the handle acts when the keeper socket is being put on or off the 100 crank handle,—see particularly Fig. VIII, to control the switches carried thereby to control the circuits associated therewith.

The insulated push pin 7 is secured to the end of the spring member 8 by screw 8', 105 which urges the same inwardly against the

spring 6. An outer spring member 9 of the switch is disposed to overlap the end of the spring 8 so that when the push pin 7 is pushed out by the action of the longitudinal spring 6 this switch is closed with a rubbing contact. The relation of these parts clearly appears in Fig. III. This is the anti-start switch. The members of this switch are connected to the conductors 16 and 17, the relations of which in the circuit will be hereafter definitely pointed out.

The structure of the anti-kick switch appears clearly in Fig. IV. The insulated push pin 10 is secured to the flexible spring member 11 by the screw 11' constituting one member of the switch. This presses against the opposite yielding member 12, and these close and complete the circuit in the conductor 33—33, as very clearly appears when the socket is on the handle. The anti-battery switch is opposite in action to this, and stands normally open when the keeper socket is on the crank handle. The yielding member 14 of the anti-battery switch, see Fig. V, is provided with an insulated push pin 13, which is secured thereto by suitable means as by the screw 14, and overlaps the member 15, so that when the pin 13 is pushed outwardly by the action of the spring 6, the circuit is broken, thus breaking the circuit between the conductors 38, 39 connected thereto, the connections of which conductors will be definitely pointed out hereafter.

The anti-start circuit is made up of the conductor 17 from the switch 7 to a yielding contact blade or member 19 suitably disposed on some part of the vehicle in position to contact with the insulated segment 20 on the lever 22, which is fulcrumed at 21. This may be the lever controlling the clutch or the gear shift lever, depending on the style of car. If a hand clutch lever is provided, it can be on that. When a gear shift lever is provided, it can be on that. The yielding contact part 18 is connected to the circuit 16 on the opposite side. This insulated part 20 is connected by the conductor 23 to binding post 23' on the dash coil 24 which is connected by a loop 23^a to binding post 38' to which is connected the conductor 38 of the anti-battery loop hereafter to be described.

When the clutch or gear shift lever 22 is in the neutral position, as indicated in Fig. I, the connected parts become a part of the battery circuit leading to the dash switch and coil 24. The battery 25 is connected at one side to the conductor 17, and at the opposite side is connected by the conductor 26 to the primary of the dash-coil. The conductor 27 leads from the timer 28 to the dash switch and coil. The conductor 29 leads from the dash switch and coil to the timer and constitutes the usual timer circuit connection and is associated in the usual way for insuring the proper timing of the spark as it

distributed through the distributor. As my invention does not pertain to these details I have not shown them.

The conductor 30 leads from the dash coil to the distributor 31, which distributes 70 through connections 32 to the spark plugs. A conductor 33 leads from the primary coil of the dash switch regularly through the anti-kick switch 10 around to the timer 37, and a conductor 33' leads therefrom to the 75 connection 34 on the insulated block 35 which connects to the late spark contact 36, which is the means for insuring the starting of the engine on the late spark only.

A loop made up of conductors 38, 39 of 80 the battery circuit connecting to binding posts 38', 39' is connected by the anti-battery switch 13, which is outside of the dash switch and coil, being located in the handle keeper socket. This serves to cut out the battery as 85 soon as the engine is started and the handle keeper socket is replaced. It thus affords an independent means of cutting out the battery automatically by means of the handle keeper socket. These switches are indicated diagrammatically in Fig. I and shown in details in Figs. II, III, IV and V, as I have already pointed out.

When the handle socket 4 is removed from the handle of the crank 3, the switches 95 7, 10 and 13 take the position indicated in Fig. I; that is, the anti-battery switch is closed, and the anti-kick and the anti-start switches are opened. The dash switch should be on the magneto, and it consequently needs no attention in starting the engine where my improved device is used, because the battery is controlled automatically by the removal of the keeper handle socket 4. 100

When the circuits are as indicated in Fig. I, it will be seen that the current from the battery passes through the switch 13 and dash coil and connections, exciting the current which is passed to the distributor and 110 to the engine when the timer is shifted to the late spark as indicated in said figure, and when the timer 37 contacts with the contact member 36 and permits the current to pass at that point. If for any reason the 115 timer has not been set to the late spark, the part 37 will be opposite the insulator 35 and no current will pass. The regular circuit 33 to the timer is broken automatically by the switch 10 when the socket 4 is removed from the crank handle. Therefore, it would be impossible, in cranking the car, to pass a spark to the engine except when the timer is set at the late spark. Also, in this connection, it will be noted that the 120 anti-start switch 7 is open, and when the circuit is open, the battery circuit will be closed only when the clutch or gear shift lever 22 is moved to the neutral position, as indicated in the said Fig. I. If, perchance, 125

the lever is moved to the position indicated by dotted lines, it will be seen that the circuit is open and the clutch is in and the engine cannot be started because no current is passing from the battery. This makes it impossible for the automobile to be started when starting the engine. The anti-kick switch is open in this condition and it is therefore impossible for the current from the dash-coil to pass through the timer except the same is connected as hereinbefore indicated to the late spark.

When the keeper is on, the anti-start switch is closed and the anti-battery switch is open, so it will be seen as soon as the engine starts and the keeper socket is put on to the crank handle, the battery is cut out, the magneto is in and the anti-kick switch is closed. This arrangement and disposition of switches I find to be highly advantageous in the dual ignition system. It is very clear that the anti-start connection could be entirely eliminated, but there would always be the danger of the starting of the car when starting the engine. Also, the anti-battery could be eliminated when it would be necessary to remember to throw the dash switch to the battery in starting. This shifting of the dash switch to the battery requires no attention with my improvements installed.

In Figs. VI to IX, inclusive, I show my invention as applied to and adapted to a Mea magneto system. In Fig. VI is the general view, showing the conductors 32 to the spark plugs of the engine 1. The crank 3 on the crank shaft 2, the return 40 and the distributor appear in the same relation and perform the same functions as in the Splitdorf structure. The handle keeper socket in this Mea system, however, is provided with but a single switch, the anti-kick switch.

The switch members 11, 12, 12', 49, 50 and screw 50' correspond to and are disposed the same as the switch members 15, 14 and 14' appearing in Fig. V and control the anti-kick circuit, said switch being disposed between the conductors 41 and 45. A contact plate 42 connected with the timer is connected to the conductor 41 of the anti-kick circuit 41-45. The conductor 45 connects to the timer, and is also continued to the dash switch. The ground or return 48 leads from the dash switch back to the magneto. An anti-start switch 46 is in the circuit 45. A contact plate 44 is secured to the top of the magneto and swings with the field magnet, which is here of an adjustable type, and is pivoted centrally so that when the timer is moved to the early spark position, this plate 44 will contact with the contact member 42 and complete the circuit and prevent the break by the timer that causes the spark.

The Mea magneto is known as a high tension magneto, furnishing a jump spark. In the Mea magneto, the armature carries a low tension primary and a high tension secondary winding connected in series. The low tension winding is ordinarily short circuited by a breaker which opens at certain points of each revolution, with the result that a high voltage is generated across the high tension winding at the moment of the break, and a spark produced across the spark gap in the cylinder to which it is connected. It will therefore be seen that when the low tension winding is short circuited that the magneto will not operate to produce the spark. I, therefore, have adapted my devices so that when the handle keeper socket is removed from the handle and the timer set at an early spark, there will be a short circuit formed so that the magneto will be inoperative to produce a spark. To accomplish this, I have added the contact 42 on the insulation 43 and the contact strip 44 to coact therewith for effecting the short circuit when the magneto is set at the early spark when the keeper is off the handle. If the keeper socket is on the handle, then the circuit is broken at the anti-kick switch thereon and the magneto will operate in the regular way, as will be seen from an inspection of the structure appearing in said Figs. VI, VII, VIII and IX.

I have described my invention with a Splitdorf magneto system and with a Mea magneto system. I have referred to these specifically but mean that they shall serve as specific description of these two classes. My invention, however, is adapted to any magneto system or any generator system, and the anti-kick feature and the anti-battery feature are adapted to use with storage batteries or dry batteries or any other source of electric energy. The anti-battery feature is, of course, only adapted for use where there are dual systems embracing a battery. Both of the systems I have illustrated make use of a jump spark for the ignition, but it is very clear that the circuits and switches which I have illustrated can be made use of in conjunction with the electric ignition apparatus where the make and break spark is employed.

The switch in the handle keeper socket is of very great advantage. As already pointed out, however, the other features of my invention can be made use of with any sort of switch means located in any suitable relation for the purpose.

The details of the structure here illustrated and described can be greatly modified and changed without departing from the broader features of my invention. I desire, however, to claim the specific structure that I have illustrated and also to claim the in-

vention broadly as indicated, and pointed out in the appended claims.

Having thus described my invention, what I claim as new and desire to secure by Letters Patent:

1. The combination in a dual ignition system of an independent insulated contact on the magneto disposed to coöperate only when the timer is adjusted to the late spark, 10 a contact piece associated with the adjustable member of the timer to coöperate therewith, connections from the said contact to the battery circuit, a loop from the main circuit, a keeper handle socket, a switch in the loop from the main circuit disposed to be closed when the socket is on the handle and to be opened when the socket is removed, a battery with a circuit suitably connected to the dash coil, a loop with a switch for controlling the battery circuit, the said switch being disposed on the keeper socket and arranged to be opened when the socket is in position and to close when the socket is removed from the handle, contact devices associated with the gear control lever positioned to close the battery circuit only when the said lever is at neutral, and an independent battery connection to coöperate with said gear control lever, with an extension to 20 a switch on the keeper handle socket, which switch is arranged to open when the keeper is off whereby the said circuit is open when the keeper is off the handle, all coacting substantially as described and for the purpose specified.

2. The combination in a dual ignition system of an independent insulated contact on the magneto disposed to coöperate only when the timer is adjusted to the late spark, 40 a contact piece associated with the adjustable member of the timer coöperating therewith, connections from the said contact to the battery circuit, a loop from the main circuit, a keeper handle socket, a switch in the loop from the main circuit disposed to be closed when the socket is on the handle and to be opened when the socket is removed, a battery with a circuit suitably connected to the dash coil, a loop with a switch for controlling the battery circuit, the said switch being disposed on the keeper socket and arranged to be opened when the socket is in position and to close when the socket is removed from the handle, and contact devices 45 associated with the gear control lever positioned to close the battery circuit only when the said lever is at neutral, all co-acting substantially as described and for the purpose specified.

3. The combination in a dual ignition system of an independent insulated contact on the magneto disposed to coöperate only when the timer is adjusted to the late spark, 60 a contact piece associated with the adjust-

able member of the timer coöperating therewith, connections from the said contact to the battery circuit, a loop from the main circuit, a keeper handle socket, a switch in the loop from the main circuit disposed to be closed when the socket is on the handle and to be opened when the socket is removed, a battery with a circuit suitably connected to the dash coil, and a loop with a switch for controlling the battery circuit, the said switch being disposed on the keeper socket and arranged to be opened when the socket is in position and to close when the socket is removed from the handle, all coacting substantially as described and for the purpose specified.

4. The combination in a dual ignition system of an independent insulated contact on the magneto disposed to coöperate only when the timer is adjusted to the late spark, 70 a contact piece associated with the adjustable member of the timer coöperating therewith, connections from the said contact to the battery circuit, a loop from the main circuit, a keeper handle socket, a switch in the loop from the main circuit disposed to be closed when the socket is on the handle and to be opened when the socket is removed, a battery with a circuit suitably connected to the dash coil, and contact devices 75 associated with the gear control lever, positioned to close the battery circuit only when the said lever is at neutral, all co-acting substantially as described and for the purpose specified.

5. The combination in a dual ignition system of an independent insulated contact on the magneto disposed to coöperate only when the timer is adjusted to the late spark, 80 a contact piece associated with the adjustable member of the timer coöperating therewith, connections from the said contact to the battery circuit, a loop from the main circuit, a keeper handle socket, a switch in the loop from the main circuit disposed to be closed when the socket is on the handle and to be opened when the socket is removed, a battery with a circuit suitably connected to the dash coil, and contact devices 85 associated with the gear control lever, positioned to close the battery circuit only when the said lever is at neutral, all co-acting substantially as described and for the purpose specified.

6. In a dual system of ignition, a keeper socket for the crank handle, switches disposed therein arranged to be automatically operated by the manipulation of said socket, and extensions from the various circuits of 90 the ignition system to said switches for automatically controlling the same, for the purpose specified.

7. In an ignition system, the combination with an adjustable timer, of an ignition 125 circuit leading therefrom, switch means for controlling the said circuit to prevent the starting of the engine when the timer is on

the early spark, and means for permitting the starting of the engine on the late spark, coacting for the purpose specified.

8. In a dual ignition system, the combination with the timer with the usual dash switch, of an extension of the battery circuit, a switch therein, and means independent of the dash switch associated with the starting device whereby the battery circuit 10 is closed on manipulation of the starting

device when the spark is retarded, as specified.

In witness whereof, I have hereunto set my hand and seal in the presence of two witnesses.
